CLAIM

The ornamental design for a centrifuging deep fryer, as shown and described.

DESCRIPTION

FIG. 1 is a front left perspective view of the centrifuging deep fryer;

FIG. 2 is a front left perspective view thereof;

FIG. 3 is a front elevation view thereof;

FIG. 4 is a back elevation view thereof;

FIG. 5 is a right elevation view thereof;

FIG. 6 is a left elevation view thereof;

FIG. 7 is a bottom plan view thereof;

FIG. 8 is a top plan view of thereof;

FIG. 9 is a back, right perspective view thereof, with a lid of the centrifuging deep fryer being open;

FIG. 10 is a front, left perspective view thereof, with the lid being open;

FIG. 11 is a bottom, front, and left perspective view thereof, with the lid being open;

FIG. 12 is a top, front, and left perspective view thereof, with the lid being open; and,

FIG. 13 is a front, left perspective view thereof, with the lid being open.

The broken lines in the drawings illustrate boundaries and form no part of the claimed design.
